Primary Examiner — Jennifer Rivard*Assistant Examiner* — April Rivas(74) *Attorney, Agent, or Firm* — Egbert Law Offices, PLLC**CLAIM**

The ornamental design for a cooler, as shown and described.

DESCRIPTION

FIG. 1 is an upper perspective view of a cooler showing my new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a lower perspective view thereof.

The features presented in broken lines represent unclaimed portions of the cooler and form no part of the claimed design.

1 Claim, 3 Drawing Sheets(56)
